UNITED STATES PATENT OFFICE.

MICHAEL J. MILMOE, OF CHICAGO, ILLINOIS, ASSIGNOR TO F. B. REDINGTON COMPANY, OF CHICAGO, ILLINOIS, A CORPORATION OF ILLINOIS.

FOLDING AND FILLING MECHANISM FOR WRAPPING MACHINES.

Original application filed March 31, 1919, Serial No. 286,345. Divided and this application filed September 15, 1920. Serial No. 410,401.

This invention relates to machines for packaging various substances, the form illustrated being especially adapted for butter and similar material.

5 The object of the invention is to provide a machine of the class named which shall be of improved construction and operation.

The invention is exemplified in the combination and arrangement of parts shown in 10 the accompanying drawings and described in the following specification, and it is more particularly pointed out in the appended claims.

This application is a division of application, Serial No. 286,345, filed March 31, 15 1919, the parts of the mechanism to which this application relates being illustrated in Figs. 1 to 8, inclusive, 12, 13, and 23 to 52, inclusive.

20 In the drawings—

Fig. 1 is a side elevation of a machine embodying one form of the present invention;

Fig. 2 is a top plan view of the machine shown in Fig. 1;

25 Fig. 3 is a front elevation of the same machine;

Fig. 4 is a rear elevation with parts in section on line 4—4 of Fig. 1;

30 Fig. 5 is a detail vertical sectional view substantially on line 5—5 of Fig. 3;

Fig. 6 is a similar view on line 6—6 of Fig. 3 looking in the opposite direction from that in Fig. 5;

35 Fig. 7 is a transverse vertical sectional view on line 7—7 of Fig. 1;

Fig. 8 is a horizontal sectional view substantially on line 8—8 of Fig. 5;

Fig. 9 is a fragmentary vertical sectional view on line 12—12 of Fig. 2;

40 Fig. 10 is a top plan view of a portion of the operating mechanism with parts in section;

Fig. 11 is a vertical section showing the carton-filling mechanism;

45 Fig. 12 is a vertical section on line 24—24 of Fig. 11;

Fig. 13 is a perspective view of the article being wrapped in the stage of the wrapping operation corresponding to Figs. 11 and 12;

50 Fig. 14 is a horizontal sectional view substantially on line 26—26 of Fig. 9;

Fig. 15 is a vertical sectional view on line 27—27 of Fig. 14;

Fig. 16 is a fragmentary vertical section 55 on line 28—28 of Fig. 14;

Fig. 17 is a fragmentary elevation; and Figs. 18 and 19 are perspective views of details;

Fig. 20 is a fragmentary vertical sectional 60 view showing one phase of the operation of a portion of the mechanism;

Fig. 21 is a perspective of part of the mechanism shown in Fig. 20;

Fig. 22 is a view similar to Fig. 20 with 65 the operating parts shown in a different position;

Fig. 23 is a perspective view of the parts shown in Figs. 20 and 22;

Fig. 24 is a fragmentary plan view of 70 parts in section showing a part of the operating mechanism in the position it assumes at one phase of its operation;

Fig. 25 is a perspective view of the article 75 being wrapped corresponding to the operating phase illustrated in Fig. 24;

Fig. 26 is a view similar to Fig. 24 showing a different phase in the operation of the machine;

Fig. 27 is a perspective view of a portion 80 of the mechanism shown in Figs. 24 and 26 and illustrating still a different phase of the operation of the machine;

Fig. 28 is a fragmentary vertical sectional 85 view showing a portion of the operating mechanism;

Fig. 29 is a perspective view of part of the mechanism shown in Fig. 28;

Fig. 30 is a view similar to Fig. 28 illustrating a different phase in the operation of 90 the machine;

Figs. 31 and 32 are perspective views of details of the machine;

Fig. 33 is a perspective view of the article 95 being wrapped at the stage illustrated in Fig. 30; and

Figs. 34 to 40, inclusive, are diagrammatic views illustrating different steps in the wrapping operation.

While the present invention is applicable to the wrapping of a large variety of articles, it is especially adapted to wrapping butter and material having similar characteristics, the embodiment of the invention illustrated in the drawings being shown as adapted to the wrapping of butter in the form of bricks as it is commonly sold upon the market. The invention contemplates 100 105

the formation of cartons from previously cut blanks of cardboard or similar material, the insertion of the wrapped bricks of butter in the cartons thus formed, and the final closing of the cartons, the whole operation being entirely automatic and without the necessity of touching either the butter or the wrappers by the hands of the operator.

The operating mechanism is supported by a suitable framework designated by the numeral 1 which is provided with a pair of bearing pedestals 2 and 3, Figs. 5 and 6, in which is journaled the main driving shaft 4 of the machine. The shaft 4 is rotated by a driving gear 5 which meshes with a pinion 6, Figs. 1, 4 and 8, the pinion 6 being formed integral with a gear 7 carried by a shaft 8 journaled in bearings 9 and 10, the gear 7 being arranged to mesh with a pinion 11 driven by a motor 12 secured to the frame of the machine, as shown in Figs. 1, 2, 3 and 7.

The bricks of butter or other articles to be wrapped, designated by the numeral 13, are fed to the machine and enfolded in a wrapper 50 and moved into the position shown in Fig. 11 by mechanism described in the application referred to above but forming no part of the invention included in the present application. When the brick is in this position a pusher 143, Figs. 11 and 12 is moved downwardly into position adjacent the rear end of the brick, and as it moves downwardly it folds the rearwardly projecting portion of the wrapper against the rear end of the brick so that the wrapper is now folded about the brick in the manner shown in Fig. 13. Extending forwardly from the upper edge of the pusher 143 is a beveled flange 144 which engages the upper face of the brick near the rear end, as shown in Fig. 11, and compresses that portion of the brick to form a slightly beveled portion shown at 145 in Fig. 13. A similar beveled portion 146 is formed at the diagonally opposite corner of the brick by the upper face of the slide rail 15, along which the brick is fed to the machine, as shown at the upper left-hand portion of Fig. 11. The purpose of these beveled corners will appear later. The pusher 142 is carried on an arm 147 which is pivotally mounted upon a sleeve 148, the sleeve being slidably carried on a rod 149. The sleeve 148 is provided with a downwardly projecting lug 150 to which a link 151 is pivotally connected. The rear end of the link 151 is pivoted to a cam lever 152, Fig. 5, which is provided with a cam roller 153 engaging a cam groove 154 in the side of the cam 137 opposite the groove 136. Rotation of the cam 137 reciprocates the pusher 143 in proper timed relation with the other parts of the machine. The end of the arm 147, opposite the pusher 143, is pivotally connected to a cam rod 155 which slid-

ably engages a cylindrical bar 156 carried by a bracket 157 secured to the arm 147. The cam rod 155 is held against lateral movement by a casing 158 secured to the top plate 30 of the frame. The lower end of the rod 155 is bifurcated, as shown in Fig. 7, and straddles the main drive shaft 4. The rod is provided with a cam roller journaled at 159 which operates in a groove 160 in a cam 161 keyed to the shaft 4. Rotation of the cam 161 oscillates the arm 147 about the shaft 149, and the cam groove 160 is so shaped that the pusher 143 is moved downwardly through the opening 141 in the top plate 85 while the arm 147 is held stationary as to its movement along the shaft 149. As clearly shown in Fig. 12, the arm 147 is provided with a gooseneck adjacent the pusher 143 which permits it to extend over the inclined folder 140 and through the slot 142 so that the pusher 143 is carried in contact with the rear end of the brick 13 during the forward movement of the pusher along the slideway formed by the rails 117 and 118. During the forward movement of the pusher 143 it is not oscillated by the cam rod 155 about the shaft 149, but remains stationary as to vertical movement until it reaches the forward end of its path of movement, at which time it passes out from beneath the forward edge of the plate 85. The arm 147 is then oscillated about the shaft 149 to raise the pusher plate 143 above the cover plate 85, after which the arm and pusher plate are drawn backwardly by the link 151 into their initial position. The forward movement of the pusher plate 143 carries the butter from the position shown in Fig. 11 entirely into the carton shown at 162 which has previously been formed and arranged in position to receive the wrapped brick, as shown in Fig. 11. Fig. 24 illustrates the pusher 143 in the act of forcing the brick 13 into the opened carton, and Fig. 25 is a perspective of the carton with the brick partially in place.

The cartons are supplied to the machine in the form of blanks, shaped as illustrated in Fig. 2. Each carton is formed with five side walls *a*, *b*, *c*, *d* and *e*. The side wall *a* is provided with an end flap *f*; the side wall *b* with an end flap *g* and a tucking flap *h*; the side wall *c* with two end flaps *i* and *j*; the side wall *d* with an end flap *k* and a tucking flap *m*; and the side wall *e* is provided with two end flaps *p* and *q*. The blanks for the cartons 162 are laid upon conveyor chains 163 which carry the blanks toward the center of the machine, as shown in Figs. 2 and 5. The chains 163 pass over sprocket wheels 164 and 165 at their forward ends, the rear ends of the chains being carried by similar sprocket wheels supported upon rearwardly extending angle bars 166 along which the blanks 162 are moved by

flights 167 on the chains 163. The sprocket wheels 164 are secured to a shaft 168 journaled in the frame of the machine and provided with a sprocket wheel 169 which is driven by a chain 170 guided over suitable idlers 171 and meshing with a sprocket wheel 172 carried by the end of the cross-shaft 96, as shown in Figs. 3 and 8. The machine frame 1 is provided with a top plate 173 which carries a pair of rails 174 and 175, Figs. 4 and 6, and these rails are provided with slots in their outer faces in which a pair of rack bars 176 slide. The rails 174 and 175 are cut away, as shown in Fig. 6, to permit engagement of the teeth of the racks by the teeth on gear wheels 177. The gear wheels 177 are fixed to a shaft 178 which is centrally provided with a pinion 179, Figs. 4 and 6, the teeth of which mesh with the teeth of a rack 180. The rack 180 is attached to a cam fork 181 which straddles the main drive shaft 4 and carries a cam roller 182 working in a groove 183 in a cam 184 on the shaft 4. Rotation of the shaft 4 imparts a reciprocation to the rack 180 which is transmitted to the two racks 176. Each of the racks 176 is provided at its forward end with a finger 185 having its front end notched, as shown in Fig. 5, for the purpose of engaging the rear edge of the carton blank. As will be seen best from Fig. 6, the angle supports 166 for the blanks 162 are provided with a downwardly inclined portion slightly in the rear of the forward run of the conveyer chains 163. Because of this inclination in the supports for the blanks, the fingers 185 in their retracted position will be below the blanks 162, but after a blank has moved downwardly along its inclined support, its rear edge will come into a position on a level with the notches in the fingers 185, so that the fingers will engage the rear edges of the blanks during their forward movement and carry the blanks into folding position, which is the position occupied by the blank in the central portion of the drawing in Fig. 2. The forward movement of the fingers 185 is sufficiently rapid to carry the blanks away from the flights 167 and prevent downward bending of the edges of the blanks as the chains pass over the sprocket wheels at the forward end of their run.

Slidably mounted in bearings 186 and 187, Figs. 2, 7 and 12, on a bracket 188 is a rod 189 which carries an arcuate hook 190 at its forward end. The rod 189 has an arm 191 rigidly secured thereto, and a link 192 is pivoted to the end of the arm 191 and to the upper end of a lever 193. The lever 193, as shown in Fig. 4, is pivotally mounted on a shaft 194 carried by brackets 195 and 196 secured to the side of the machine frame 1. The lever 193 is pivotally connected at its lower end, as shown in Figs. 4 and 8, with a

cam rod 197 which straddles the main drive shaft 4 and is provided with a roller 198 traveling in a groove 199 in a cam 200 secured to the shaft 4. Rotation of the cam 200 reciprocates the rod 189 in its bearings 186 and 187 which imparts a similar reciprocation to the hook 190 on the end of the rod. As shown in Figs. 9, 20, and 21, a pair of angle bars 201 are carried at the end of a pair of arms 202 in position to form a continuation of the outermost angle bar 166 on which the carton blanks are fed to their central or folding position. The other angle bar 166 has its inner end in alinement with an extension 203 on the bracket 188, the extension 203 having its edge curved, as shown at 204, to overlie the edge of the blank 162 as it is pushed from the end of the angle bar 166 by the fingers 185. The edge of the blank 162, adjacent the extension 203, is supported by a plate 205 provided with a downwardly extending portion 206. The plate 205 is secured to and supported from the projection 203. The angle bars 201 and their supporting arms 202 are spaced from one another to provide a slot in which the hook 190 travels, and this hook is in the position illustrated in Fig. 9 when the blank 162 is fed into its folding position by the fingers 185. The forward arm 207 of the hook 190 extends below the level of the blank 162, and the rear arm 208 terminates slightly above the upper face of the blank. After the blank is in the position shown in Fig. 9, the rod 189 is drawn inwardly and the edge of the blank strikes the inner curved surface of the hook 190, and since the blank is held by the curved abutment 204, the blank will be caused to bend along the scored lines by which the sides *a*, *b*, *c*, *d*, and *e* are separated, so that the blank will roll into the form shown in Figs. 20 and 21. This will bring the side *c* so that its outer face is just inside the plane of the inner face of the plate 209 which supports the arms 202, and which with the plate 206 forms the walls of a filling pocket for the carton.

A pair of forked members 210 are supported by downwardly extending rods 211 carried on an arm 212, the rods 211 being located on opposite sides of the bar 189, as shown in Figs. 2 and 5. The arm 212 is connected to the upper end of a vertically moving bar 213 which slides in bearings 214 and 215, Fig. 4. A collar 216 is fixed to the bar 213 and is connected by a link 217 with a lever 218 pivoted on a pin 219 on the frame of the machine, as shown in Figs. 7 and 8. Each of the forks 210 is provided with a long prong 220 and a short prong 221. When the carton is rolled into folded position it will pass beneath the short prong 221, as shown in Fig. 20, but will strike the lower end of the long prong 220. When the carton reaches the position shown in this figure, the

forks 210 will begin to move downwardly and will carry the carton with it in the manner illustrated in Fig. 22 into the filling pocket. As the carton moves downwardly, 5 the side wall *e* will be folded by the inclined corner between the plates 205 and 206 inwardly against the outer face of the prongs 220, as shown in Fig. 22. A pair of hooks 222 are pivoted at 223 on each side of the 10 plate 206 and have their rear faces connected by a bar 224 which is pressed inwardly by a spring 225 having its rear end abutting against a bracket 226 carried by the plate 205. The downwardly moving carton forces 15 the hooks 222 backwardly against the tension of the spring 225 until the carton has passed the shoulders of the hooks, at which time the hooks spring inwardly and hold the carton in place during the upward movement of the fork 210. The prongs 221 of 20 the forks 210 are sufficiently separated to pass on opposite sides of the plate 209, as illustrated in Fig. 22. The plate 209, as shown in Fig. 9, is secured by screws 227 to 25 a block 228 which is carried on standards 229 and 230, the block being provided with a rearwardly extending plate portion 231 which rests upon the standards 230. The block is removably held in place on the standards 229 by a cross-bar 232, and the plate 231 is removably secured to the standards 230, see Fig. 14, by arms 233 connected with sleeves 234 mounted on pivot pins 235. The arms 233 are pressed outwardly by springs 30 236, and the upper ends of the sleeves 234 are connected with hand grips 237, by means of which the arms 233 may be swung inwardly against the tension of the springs 236 and freed from slots in the upper ends of the standards 230 to release the block 228 so 35 that it may be removed from the machine frame. The bar 232 is held in place by screws at its ends, and is also removed prior to the removal of the block 228. The block 40 228 and plate 231 are made thus easily removably in order to give ready access to the parts adjacent the filling pocket. A pair of bracket bars 238, Figs. 14 and 20, are secured by screws 239 to the sides of the block 45 228 and carry a pivot shaft 240 at their outer ends. A pair of fingers 241 are fixed on the ends of the shaft 240 in position to swing vertically along the edges of the plate 209. The ends of the fingers 241 swung into 50 their uppermost position engage the carton at the side opposite the hooks 222 as the carton is moved downwardly by the forks 210, thus equalizing the resistance to the downward movement of the carton and preventing distortion of the carton as it is moved into the filling pocket. In order to provide a uniform resistance to the downward movement of the fingers 241, the central portion of the shaft 240, Figs. 9 and 14, 55 is provided with a brake segment 242 which

is secured to the shaft 240 to turn with the fingers 241. A brake shoe 243 bears against the segment 242 under the pressure of a spring 244 housed in the block 228. A link 245 is pivoted at 246 to the segment 242 and is provided with a slot 247 through which a pin 248 passes. The pin 248 is connected with a reciprocating member 249, operated in a manner to be described, so that it causes the pin to engage the end of the slot 247 at 70 the proper time in the operation of the machine to restore the fingers 241 to their uppermost position after a carton has been filled and moved out of the filling pocket. 75

A plate 250, as shown in Fig. 9, extends transversely of the machine beneath the filling pocket and forms a slideway onto which the filled cartons are lowered in a manner to be described, and along which they are moved from the machine after the end flaps of the carton have been closed. A plunger 251 is mounted to reciprocate above the plate 250 and is provided on its upper face with rearwardly projecting fingers 252, see Fig. 18, which form the support for the carton while in filling position, as shown in Fig. 9. The plunger 251 is connected with the forward end of a reciprocating bar 253, the rear end of which bar is connected by a link 254 with a cam lever 255. The cam lever 255 is pivotally mounted on the shaft 194 and is rigidly connected with an inwardly projecting arm 256 which carries a roller 257 at its inner end, Figs. 7 and 8, arranged to bear in a groove formed in the face of a cam 258 secured to the shaft 4. Rotation of the cam 258 reciprocates the plunger 251 to perform its various operations, as will be described. 90

While the carton is held in the filling position and supported by the plunger 251, the brick of butter which has been wrapped in the manner previously described is forced into the carton from the left, as viewed in Fig. 11, which is the same as the lower side of the drawing in Fig. 24. In order to hold the carton from sliding during the time that the butter is being forced into it a finger 259 is caused to bear upon the flap *k*. The finger 259 is fixed to a rock shaft 260 which has an arm 261, Figs. 5 and 15, secured thereto, the arm being connected with a cam rod 262 which carries a roller 263 at its lower end arranged to operate in a groove 264 in the cam 45. After the carton has been folded and moved into the filling position, the shaft 260 is rocked to cause the finger 259 to grip the end flap of the carton, as shown in Fig. 11. The rod 262 is made in two parts having an interposed spring 262' to render, resilient, the gripping action of the finger 259. 100

After the brick of butter is moved into the carton, the end flaps are closed by mechanism which is shown in Figs. 14, 24, 26 and 110

27. A rod 265 is mounted to slide in the block 228 and in a bearing 266 projecting upwardly from the outer end of the plate 23. The rod 265 has fixed thereto the member 249 which carries laterally projecting arms 267 and 268. Pivotaly mounted at the end of the arm 267 is a lever 269 which carries a flap-closing plate 270 at one end and which is provided with a pin 271 projecting downwardly from the other end. The pin 271 is arranged to travel in a cam slot 272 formed in a plate 273 which is fixed to the upper surface of the plate 231. The arm 268 carries a lever 274 provided with a flap-closing plate 275 and a pin 276 arranged to travel in a cam slot 277. Both of the levers 269 and 274 are provided with spring-pressed brakes 278, as shown in Fig. 24, to hold their respective levers in any angular position into which they are turned until they are positively moved from that position. The rod 265 is slid longitudinally in its supports by a sleeve 279 which has a limited rotary movement about the rod, as shown in Fig. 15, but which is held against longitudinal movement by a collar 280. The member 249 is held from rotation about the rod 265 by a bar 281 mounted on the plate 231, as shown in Fig. 15. The sleeve 279 carries an arm 282 provided with a socket 283 at its outer end, the lower side of the socket being open so that it may be swung into and out of engagement with a pin 284 on a lever 285, as shown in Figs. 14 and 15. The lever 285, as shown in Figs. 7 and 8, is pivotally mounted on a pin 286 carried on a bracket 287 secured to the frame of the machine. The lower end of the lever is provided with a cam roller 288 which engages a groove 289 in a cam 290, Fig. 6, keyed to the shaft 4. Rotation of the cam 290 reciprocates the rod 265 which carries with it the arms 267 and 268 and their respective flap-closing plates. It should be noted that the plate 270 extends inwardly a greater distance than the plate 275, as shown in Fig. 24, and the forward movement of the rod 265 causes the pin 271 to travel along the inclined wall 291 of the groove 272 to cause the plate 270 to be swung into the position shown in Fig. 24, closing the end flap *i* of the carton. The parts reach the position shown in Fig. 24 prior to the filling of the carton so that the plate 270 assists in holding the carton in place during the movement of the brick 13 into the carton. The plate 275 does not engage the end flap *j* until the carton has been filled and the pusher 143 raised out of engagement with the end of the brick. It should be noted that the plates 270 and 275 when they first strike their respective flaps are in their outer position and are moved inwardly by the inclined portions of their cam groove after the front edges of the plates have come into contact with the flaps to be closed. Fig. 26 shows both plates 270 and 275 moved to their innermost position holding their respective flaps closed, while at the left of the figure, corresponding plates 292 and 293 are shown in the act of closing the flaps *p* and *q* on the other side of the carton. It will be seen that the folding of the end flaps of the carton carry inwardly with them the end folds on the paper wrapper, thus completing the wrapping operation simultaneously with the folding of the end flaps. The flaps at one side of the carton are folded slightly in advance of the flaps on the other side, as shown in Fig. 26, so that the end flaps are made to overlap one another. The plates 292 and 293 are carried respectively by arms 294 and 295 pivotally mounted on projections 296 and 297 on a sleeve 298 fixed to the end of a sliding rod 299. The rod, as shown in Fig. 9, slides in bearings 300 and 301 carried on the frame of the machine and is reciprocated by a lever 302 connected to the rod by a link 303. The lever 302 is pivotally mounted, as shown in Figs. 7 and 8, upon the shaft 194, and its lower end 304 projects inwardly and carries a cam roller 305 which travels in a groove 206 in the cam 290. The arms 294 and 295 are provided with pins 307 which project into cam grooves 308 formed in plates 309 carried at the sides of the bearing block 300. A link 310 is pivotally mounted at 311 on the arm 295 and is provided with a slot 312 in its opposite end through which a pin 313 extends into the arm 294. The pin 313 is surrounded by a coil spring 314 and bears upon a washer 315 to produce frictional engagement between the arm 294 and the link 310. During the inward movement of the arms 294 and 295 they travel in a straight line in their outermost positions until the front ends of the plates 292 and 293 have engaged the flaps and begun their closing movement. Further movement of the arms causes them to travel along the inclined portions of their cam grooves which swings the plates 292 and 293 inwardly to close the end flaps, as shown in Fig. 27. The return movement of the arms will carry the plates in a different path from that traveled during their inward movement, for they will be held in their closed position by the friction between the link 310 and the arm 294, so that they will travel backwardly in a straight line until they have been withdrawn from engagement with the closed flaps, at which time the pins 307 will again strike an inclined portion in the cam grooves, and the plates will be opened ready for a second operation. The plates 270 and 275 follow a similar path of movement due to the shape of their cam grooves and the brake members 278 arranged at the pivotal connection between the levers 269 and 274 and their supports.

Before the plate 292 is entirely withdrawn from engagement with the flap *g*, the overlapping end flap *a* is swung downwardly to hold the flaps *g* and *i* in place. The movement of the flap *a* is produced by a finger 316. Figs. 28 and 30, pivotally mounted at 317 on a rocker arm 318. The finger 316 is provided with a cam roller 319 which bears upon a cam 320 carried on the plate 173 of the machine frame. A spring 321 normally forces the finger 316 upwardly and the cam roller 319 downwardly into engagement with the upper face of the cam 320. Rotation of the arm 318 in the direction of the arrow in Fig. 40 carries the finger 316 inwardly from the position shown in Fig. 30 to that shown in Fig. 28. Further movement of the arm in the same direction causes the roller 319 to travel along the steeper part of the cam 320, so that the end of the finger is moved downwardly in an almost vertical line to close the flap *g* against the end of the carton. The arm 318 is secured to a shaft 322 journaled in the sides of the machine frame, as shown in Fig. 4, and provided with an arm 323, Fig. 6, the end of which is pivoted to a link 324 having a cam fork 325 at the opposite end which straddles the shaft 96. The cam fork 325 is provided with a roller 326 which engages a groove in the cam 103 secured to the shaft 96.

After the carton 162 has been filled and the flaps closed, as described, the plunger 251 is withdrawn from beneath the carton and the carton is moved downwardly onto the plate 250. During the downward movement of the carton it is supported by a U-shaped plate 328, the legs 329 of which project upwardly to engage the ends of the carton on opposite sides of the plunger 251, as shown in Fig. 28. The plate 328 is supported by a bar 330, Fig. 5, which carries a cam roller 331 at its lower end arranged to engage a cam groove 332 in the cam 258. Secured to the lower surface of the plate 328, as shown in Fig. 9, is a bracket 333 having a pair of arms 334 pivoted thereon and connected by a cross-plate 335. A lever 336 projects downwardly from the cross-plate 335 and is provided with a cam roller 337 at its lower end, as shown in Fig. 7. The roller 337 operates in a groove formed in an upright bar 338 which is rigidly carried by a rod 339 mounted to slide in a bearing bracket 340 and a bearing sleeve 341 carried by the frame of the machine. The end of the arm 339 is connected by a link 342 to the lever 255 which operates the plunger 251. The upper ends of the arms 334 are provided with hooks 343 arranged to be swung into engagement with the upper face of the filled carton when the plate 328 is in its uppermost position and the carton is in the filling pocket. As the plunger 251 is withdrawn from beneath the filled carton, the hooks 343 will be swung in-

wardly, as will be apparent from Fig. 7, to cause the hooks to engage the upper face of the filled carton when the plunger has been withdrawn from beneath it. This will leave the carton resting upon the upper edges of the legs 329 of the U-plate 328 with the hooks 343 holding the carton in place upon the U-plate, as illustrated in Figs. 28 and 29. When the parts are in this position, the bar 330 is lowered by the rotation of the cam 258, and the U-plate 328 and hooks 343 move downwardly in unison with one another to lower the filled carton out of its filling pocket. It will be apparent from Fig. 28 that during the lowering movement of the carton, the end flap *k* will be folded inwardly by the rounded ends of the slide rails 117 and 118. At the same time the flap *g*, which has been closed by the finger 316, will pass within the outwardly turned upper edge 344 of a plate 345 secured to the end of a bar 346, and shown in perspective in Fig. 31. The bar 346 is supported by the standards 229 and 230, as shown in Fig. 9, and extends parallel to the slide plate 250 to form a guide for one end of the cartons as they are slid out of the machine. When the filled carton is brought into engagement with the upper face of the plate 250, the end flaps will be held closed, as shown in Fig. 30, and the carton will rest upon the plate 250 in front of the plunger 251 so that a second forward movement of the plunger will carry the carton 162 into the position at the right of the plunger in Fig. 9, which shows the plunger just before it has reached its extreme inner position. After the plunger has reached its extreme movement to the right, as viewed in Fig. 9, it will leave the inner face of the carton in alignment with the inner face of the plate 209, in which position the flaps *m* and *h* are tucked in place, which is the last operation to be performed.

The mechanism for tucking the flaps *m* and *h* is shown in Figs. 15 to 19, inclusive, and the steps of the tucking operation are illustrated diagrammatically in Figs. 34 to 40, inclusive. Fig. 34 shows the carton in the condition in which it is left by the plunger 251 when it is pushed away from beneath the filling pocket into the slideway above the plate 250. A pair of levers 347 and 348 are pivotally mounted at 349 and 350, respectively, on opposite sides of the slideway, and the lever 347 is provided with a series of downwardly projecting fingers 351 for engaging the tucker flap *m* of the end flap *k*, while the lever 348 is similarly provided with upwardly projecting fingers 352 for engaging the tucker flap *h* of the end flap *g*. The pivot 349 for the lever 347 is carried by the bracket 353 which supports the ends of the slide rails 117 and 118. The pivot 350 for the lever 348 is carried on a support 354 secured to the top plate of the

machine frame, as shown in Fig. 10. The lever 348 is provided with a coil spring 355 which normally raises the rear end of the lever into engagement with a stop 356 which 5 throws the fingers 351 downwardly into the position shown in Fig. 34. A similar spring 357 throws the forward end of the lever 347 upwardly holding the fingers 352 in the position shown in Fig. 34. The rear ends of 10 the levers 347 and 348 are provided with pins 358 and 359, respectively, the pin 358 being located in position to strike the upper beveled surface of a bar 360 projecting rearwardly from the plunger 251. The pin 359 15 is similarly arranged in position to strike the lower beveled surface of a bar 361 projecting rearwardly from the opposite side of the plunger. When the plunger is in its forward position, as shown in Fig. 17, the 20 front ends of the levers 347 and 348 with their fingers 351 and 352 will be held in retracted position by the springs 355 and 357, but when the plunger 251 is moved backwardly from beneath the filling pocket, the 25 bars 360 and 361 will strike the pins 358 and 359 and force the fingers 351 and 352 inwardly into the position illustrated in Fig. 37.

Cooperating with the fingers 351 and 352 30 are tucker hooks 362 and 363, the hooks being spaced apart, as shown in Fig. 19, to permit the fingers 351 and 352 to enter the spaces between the hooks. The hooks 362 are carried on a block 364 secure to the front 35 end of a slide 365 which is supported on the upper face of the top plate 30 and held in place by guides 366, Fig. 10. The hooks 363 are similarly carried by a block 367 secured to the end of a slide 368 which is held 40 in place on the top plate 30 by guides 369. The lower faces of the slides 365 and 368 are provided with lugs 370 having rectangular blocks 371 pivotally carried thereby. A bracket 372 is secured to the machine frame 45 1, as shown in Fig. 16, and carries a pair of bell crank levers 373 pivotally mounted thereon. The upper ends of the levers 373 are bifurcated to engage the pivot blocks 371 of the slides 365 and 368. The lower 50 arms of the levers 373 are similarly bifurcated to engage pivot blocks 374 carried by the upper end of a vertically reciprocating bracket 375, shown also in Fig. 7. The bracket 375, as shown in Fig. 6, is formed integral with the cam fork 376, which straddles the main drive shaft 4, and is provided with a cam roller 377 which travels in a groove 378 in a cam 379 secured to the shaft 4. Rotation of the cam 379 oscillates the bell crank levers 373 about their pivots and reciprocates the slides 365 and 368 in their guides. The bifurcated ends of the bell crank levers 373 are given sufficient sliding movement upon their rectangular pivot 55 blocks to compensate for the arcuate move- ment of the ends of the bell crank levers. The timing of the movement of the fingers 351 and 352 relative to the tucker hooks 362 and 363 will best be understood from Figs. 34 to 40, inclusive. It should be noted in 70 these figures that the bar 346 which bears against the upper right-hand corner of the carton is rounded at its lower inner edge, as shown at 380, and that a guide plate 381 which engages the lower left-hand corner 75 of the carton is similarly rounded at 382. The guide plate 381 is secured to the slide plate 250, as shown in Figs. 16 and 20. After the carton is moved from the position indicated in Fig. 30 to a position in alignment with the operating parts of the tucking mechanism to the right of the filling pocket, as viewed in Fig. 9, the parts will be in the relative position shown in Fig. 34. The tucking hooks 362 and 363 will then be 80 moved inwardly, as indicated in Fig. 35, to fold the tucking flaps *m* and *h* inwardly over the edges of the side walls *b* and *d*, the flaps being folded against the outer faces of the side walls. When the hooks 362 and 90 363 reach their innermost positions, the shoulders 383 on the ends of the hooks will engage the edges of the tucker flaps, which action will be assisted by the resiliency in the flaps, which tends to spring them outwardly into contact with the shoulders. The tucker flaps are provided with beveled portions 384 which press against the folded portions of the flaps and assist the tendency 95 of the flaps to spring outwardly. As soon as the flaps are engaged by the shoulders 383, the tucker flaps are then withdrawn into the position shown in Fig. 36. This will spring the end flaps *g* and *z* backwardly, but the resiliency of the end flaps will hold 100 the tucker flaps in engagement with the shoulders 383. The rounded portions 380 and 382 of the guide members 346 and 381 assist in this springing tendency of the end flaps. By the time the parts are in the position shown in Fig. 36, the plunger 251 has 105 been sufficiently retracted to bring the beveled ends of the bars 360 and 361 into engagement with their respective pins 358 and 359, so that the levers 347 and 348 are oscillated to move the fingers 351 and 352 inwardly to force the tucker flaps *m* and *h* past the edges of the side walls *b* and *d*, as 110 shown in Fig. 37. During this inward movement of the fingers 351 and 352, the tucker hooks remain stationary and the fingers push the edges of the tucker flaps free of the shoulders 383. The inward movement of the fingers 351 and 352 brings the tucker flaps more nearly into a horizontal position 115 so that the edges of the flaps will free themselves from the notches in the ends of the fingers. This will permit the tucker flaps to spring inwardly into the position shown in Fig. 38, the fingers 351 and 352 holding 120 125 130

the flaps sufficiently within the plane of the side walls *b* and *d* to make sure that the edges of the flaps will not strike the edges of the side walls. As has been previously 5 stated, the diagonally opposite corners of the brick of butter were beveled off by the slide bar 15 and the flange 144 so that sufficient space is provided to insure the entrance of the tucker flaps *m* and *h* between the side 10 walls of the carton and the surface of the brick of butter. To insure the movement of the tucker flaps into the space thus provided, the blocks 364 and 367 are given a slight movement inwardly into the position 15 shown in Fig. 38 to start the tucker flaps into place in case the resiliency of the end flaps fails to perform this movement. By the time the parts have reached the position shown in Fig. 38, the plunger 251 has 20 reached its extreme outer position and has begun to move inwardly again to engage the next carton, so that the pins 358 and 359 are freed from the bars 360 and 361, and the fingers 351 and 352 are consequently again 25 moved outwardly into the position shown in Fig. 39. This permits the tucker flaps *m* and *h* to spring outwardly into contact with the inner face of the side walls *b* and *d*, and to facilitate this outward movement of the 30 tucker flaps the blocks 364 and 367 are backed away slightly from engagement with the end flaps so that the flaps are left free and unrestrained to assume the position shown in Fig. 39. The parts remain in the 35 position shown in Fig. 39 only momentarily, after which the blocks 364 and 367 again move inwardly to the position shown in Fig. 40 and force the tucker flaps completely home within the side walls of the carton. 40 This movement completes the wrapping operation and the blocks 364 and 367 are withdrawn from engagement with the ends of the carton in time to permit the completely wrapped brick and carton to be moved out 45 of the way along the slide plate 250 as the next carton is being moved into the tucking position by the plunger 251. The finished cartons are thus continuously forced outwardly along the side plate 250 away from 50 the machine where they are received and packed ready for shipment. The carton requires no gluing, for the reason that the end flaps are held in place by the tucker flaps and the outermost overlapping side 55 wall *e* is provided with end flaps *p* and *q* at each end which when bent inwardly and enclosed by the other end flaps prevent the outer side wall *e* from becoming unfolded.

60 The operation of the various parts has been described in connection with the description of the parts, and it is thought that further description of the operation, as a whole, will be unnecessary. It will be apparent that the operation of the machine is 65 continuous and that the bricks of butter

are wrapped and placed in cartons entirely automatically without the necessity of the wrappers or bricks being touched by the hands of operators.

I claim:—

1. In combination, a support for a carton blank, a member having an inclined surface for engaging one edge of said blank, and means for moving said member relative to said blank to cause the edge of said blank to travel along said inclined surface to fold said blank into the form of an open carton. 75

2. In combination, a support for a carton blank, a member having an arcuate surface arranged to engage one edge of said blank, and means for moving said member relative to said blank to cause the edge of said blank to travel along said arcuate surface to fold said blank into the form of a 80 carton. 85

3. In combination, a support for a carton blank and a folder for said blank, said folder having an inclined surface for engaging the edge of said blank, and a holding member having a fixed position relative to said surface for engaging said blank, during a folding operation at a point spaced from said edge thereof. 90

4. In combination, a support for a carton blank, a folder for said blank having an arcuate surface for engaging one edge of said blank, a contact member for engaging said blank at a point spaced from said edge thereof, and means for moving said folding member relative to said blank to roll said blank 100 into the form of a carton. 95

5. In combination, a support for a carton blank, an abutment for engaging one edge of said blank, a folder for engaging the opposite edge of said blank means for engaging said blank intermediate said edges during a folding operation, and means for moving said folder toward said abutment to fold said blank into the form of a carton, said 105 engaging means being movable in unison with said folder. 110

6. In combination, a support for a carton blank, an abutment for engaging one edge of said blank, a folder having an arcuate surface for engaging the opposite edge of said blank, a contact member for engaging said blank at a point removed from the portion thereof engaged by said arcuate surface, and means for moving said folding member 115 toward said abutment to roll said blank within said arcuate surface into the form of a carton. 120

7. In combination, a support for a carton blank, a folder comprising an arcuate hook having an opening therein, means for positioning a carton blank on said support so that the edge of said carton projects through said opening into said hook, and means for moving said folder relative to said support 125 to roll said blank into the form of a carton. 130

8. In combination, a support for a carton blank, an arcuate folder for said blank, means for positioning a carton on said support so that it projects into said arcuate folder, and means for moving said folder along said support to cause the carton blank to enter said arcuate folder and to be formed into a carton within said folder.
9. In combination, a support for a carton blank, an arcuate folder for said blank having an opening in the periphery thereof, means for positioning a carton on said support so that one edge of said carton projects through said opening into said arcuate folder, means for moving said folder relative to said support, and means for holding said blank against movement on said support to cause said blank to enter said arcuate folder during the movement of said folder and be rolled therein into the form of a carton.
10. In combination, a support for a carton blank, means for preventing movement of said blank on said support, an arcuate hook for engaging one edge of said carton, and means for drawing said hook along said support to fold said carton blank.
11. In combination, a support for a carton blank, a plunger rod movable relative to said support, means for retaining a carton blank in position on said support, and a hook on said plunger rod for engaging one edge of said blank to fold said blank into the form of a carton when said plunger rod is moved relative to said support.
12. In combination, a support for a carton blank, an abutment member at one edge of said support, an arcuate folder movable relative to said support toward and away from said abutment member, means for feeding a carton onto said support so that one edge engages said abutment member and the opposite edge thereof enters said arcuate folder when said arcuate folder is moved away from said abutment member, and means for moving said arcuate folder toward said abutment member to cause said blank to be rolled in said folder into the form of a carton.
13. In combination, a support having a filling pocket therein, means for positioning a carton blank on said support above said filling pocket, means for folding said blank into the form of a carton with the outermost side away from said pocket closed, and means for forcing said blank into said filling pocket.
14. In combination, a frame having a pocket therein, means for positioning a carton blank on said frame above said pocket, means for partially folding said blank into the form of a carton with the side away from said pocket closed while said blank is in position above said pocket, and means for engaging said closed side for forcing said blank into said pocket to further fold said blank.
15. In combination, a frame having a pocket therein, means for positioning a blank on said frame above said pocket so that said blank projects beyond said pocket on opposite sides thereof, means for folding the projecting portion of said blank on one side of said pocket to form a closed figure above said pocket, and means for engaging the portion of the blank thus folded to force said blank into said pocket and to fold the projecting portion of said blank at the opposite side of said pocket against the portion already folded.
16. In combination, a support for a carton blank, means for folding a portion of said blank to form an open carton, a stop device for engaging the folded portion of said blank, and means for shifting said stop device to perform a further folding operation of said blank.
17. In combination, a support for a carton blank, means for rolling said blank on said support into the form of a carton, a stop device having a finger thereon for engaging the folded portion of said blank, and means for moving said stop device to transfer the folded blank relative to said support.
18. In combination, a support for a carton blank, a folder for rolling a blank on said support into the form of a carton, a bifurcated member positioned above said support and having the prongs thereof of unequal length so that the blank as it is being folded will pass one of said prongs and be engaged by the other thereof, and means for moving said bifurcated member to cause said prongs to engage opposite sides of the folded blank.
19. In combination, a support for a carton blank having an opening therein, means for positioning a blank on said support above said opening, means for partially rolling said blank into the form of a carton above said opening, a plunger for engaging the partially folded carton and moving said carton into said opening, and means for further folding said blank as it is moved into said opening.
20. In combination, a frame having a pocket therein, means for moving a blank divided by score lines into five parts onto said support so that one of the divisions of said blank will be positioned above said pocket and three of the divisions will project on one side of said pocket and one division on the other side thereof, means for folding the three projecting division to form a rectangular figure above said pocket, and means for forcing the blank thus folded into said pocket to fold the remaining division of said blank.
21. In combination, a support for a carton having an end flap thereon, means for moving an article into said carton, and means for

holding said carton against movement while said article is being moved into said carton, said holding means comprising a device for forcing said end flap against said support 5 and gripping said flap between said device and support to hold the carton against the force exerted thereon by the movement of said article into the carton.

22. In combination, a frame having a 10 slideway therein, means for positioning a carton having an end flap thereon at one end of said slideway so that said end flap will project into said slideway, means for engaging opposite faces of said end flap to grip 15 the same at opposite points on said faces thereby holding said carton against movement relative to said slideway, and means for forcing an article along said slideway into said carton while said carton is held against 20 movement by said end flap.

23. In combination, a support for a carton having an end flap thereon, means for engaging said end flap and for pressing it downwardly and gripping said blank against said support, thereby holding said carton from movement on said support, and means for sliding an article over the end flap thus held into said carton.

24. In combination, a support for a carton to be filled having an end flap thereon, means for moving an article into said carton while said end flap is open, a pivoted finger in the path of movement of said article, and means for moving said finger into 35 gripping engagement with said end flap to permit said article to move over said finger and end flap and to hold said carton against movement as said article is forced into said carton.

40 25. In combination, a frame having an opening therein, means for moving a carton into said opening, retaining mechanism arranged to non-symmetrically engage said carton as it is moved into said opening, and 45 a resistance member for engaging said carton as it is moved into said opening to prevent distortion of said carton.

26. In combination, a frame having an 50 opening therein, means for moving a carton into said opening, and means for engaging opposite portions of said carton as it is moved into said opening to offer yielding resistance to the movement of said carton into said opening, the engaging means for one portion 55 of said carton comprising means for retaining said carton while the engaging means for the other portion offers resistance to movement of the carton in one direction only.

60 27. In combination, a frame having an opening therein, means for moving a carton into said opening, a catch member for engaging one side of said carton as it is moved into said opening, and a frictionally held resistance member for engaging an opposite portion 65 of said carton to prevent distortion of

said carton as it is moved into said opening.

28. In combination, a frame, folding mechanism carried by and movable transversely of said frame and having a portion thereof spaced slightly therefrom, said portion maintaining a substantially uniform distance from said frame for all positions of said folding mechanism, and reciprocating inclined fingers for moving a blank edgewise between said frame and spaced portion into 70 75 position on said frame to be engaged by said folding mechanism.

29. In combination, a frame, folding mechanism carried by and movable transversely of said frame and having a portion spaced 80 slightly from the surface thereof, said portion maintaining a substantially uniform distance from said frame for all positions of said folding mechanism, a conveyer for carrying blanks toward said folding mechanism, and reciprocating inclined fingers for transferring said blanks edgewise along the surface of said frame from said conveyer into position between said frame and spaced portion to be engaged by said folding mechanism. 85 90

30. In combination, a frame having a pocket therein, mechanism for feeding a carton with open ends into said pocket, means for placing an article in said carton while in 95 said pocket, and a support for said carton while in said pocket, said support being movable to permit said carton to be lowered out of said pocket after said article is placed therein. 100

31. In combination, a frame having a pocket therein, means for moving a carton to be filled into said pocket, a spring catch at one side of said pocket for holding said carton in position in said pocket and a resistance member at the opposite side of said pocket movable with said carton as it enters said pocket. 105

32. In combination, a frame having an opening therein for receiving a carton, means for moving a carton into said opening, said moving means having a finger thereon for engaging one side of said carton, means for folding a flap of said carton against said finger, means for withdrawing said finger, 110 and a spring-pressed member for closing said flap against said carton after said finger is withdrawn therefrom. 115

33. In combination, a frame for holding a carton, means for moving an article into said carton, a device for closing an end flap on said carton, and means for moving said flap-closing device transversely of the plane of the end of said carton to close said flaps and to bring said device into engagement with said carton to prevent movement of said carton while said article is being placed therein. 120 125

34. In combination, a frame for holding a carton having end flaps thereon, a device for engaging an open flap on one end of said 130

carton for holding said carton in place on said frame, and a separate device for engaging a closed flap at the opposite end of said carton to assist in holding said carton in place on said frame.

35. In combination, a support for a carton to be filled, means for moving an article into said carton from one end thereof, and means for closing a flap at the opposite end of said carton, said closing means being movable transversely of the end planes of said carton into position for bearing against said closed flap to hold said carton against movement during the filling thereof.

36. In combination, a support for a carton to be filled, a pair of devices for closing flaps at opposite ends of said carton, means for moving one of said devices into engagement with a flap at one end of said carton to close said flap and retain said carton in position while said carton is filled through the opposite end thereof and for subsequently moving the other of said devices into engagement with a flap at the said opposite end of said carton so that said devices will close said flaps successively and permit filling of said carton between said closing operations.

37. In combination, a support for a carton to be filled, means for moving an article into said carton from one end thereof, means movable transversely to the end planes of said carton for closing a flap at the opposite end of said carton and for bearing against said flap to prevent movement of said carton during the filling thereof, and means for closing a flap at the end of said carton through which said carton is filled subsequent to the filling operation.

38. In combination, a support for a carton having end flaps thereon, a device for closing one of said flaps, a cross-head for moving said closing device transversely to the axis of said carton and a cam for guiding said device in the direction of said axis to swing said flap into closed position while permitting withdrawal of said closing device by movement in a path at right angles to the axis of said carton.

39. In combination, a support for a carton to be filled, a contact member for closing a flap on said carton, a cam for guiding said contact member for closing said flap in a direction transverse to the plane of said flap when closed, and means for moving said contact member in a direction parallel to the plane of said flap to withdraw said contact member after said flap has been closed said cam being inactive during the withdrawal of said member.

40. In combination, a support for a carton having closing flaps thereon, a flattened contact member for enclosing one of said flaps, a cam for guiding said flattened member in a direction transverse to the plane thereof for closing said flap, means for closing a

second flap against the face of said contact member, and means for withdrawing said contact member in the direction of the plane thereof said cam being inactive during the withdrawal of said member.

41. In combination, a support for a carton to be closed, a pivoted member for closing a flap on said carton, means for moving said pivoted member toward said carton and for swinging said member about its pivot during said movement, and a frictional device for holding said member in the position on its pivot to which it is swung until it is positively moved into another position.

42. In combination, a support for a carton to be closed, a pivoted member for closing a flap on said carton, and a frictional device for preventing accidental movement of said member about its pivot.

43. In combination, a support for a carton to be closed, a contact member for closing a flap on said carton, and a device having a cam for guiding said contact member to travel in one path during the closing operation thereof and a second cam for guiding said device in a different path as said contact member is withdrawn from said carton.

44. In combination, a support for a carton to be closed, a pivoted contact member for closing a flap on said carton, means for moving the pivotal support of said contact member toward and away from said carton, and a guide having a pair of cam faces for controlling the position of said contact member on its pivot during the movement of said member toward and away from said carton.

45. In combination, a support for a carton to be closed, a pivoted contact member for closing a flap on said carton, means for moving the pivotal support of said contact member toward and away from said carton, a cam having a surface arranged to swing said contact member about its pivotal support as it is moved toward said carton, a separate surface for controlling said member during the withdrawal of said member from engagement with said carton, and a frictional device for preventing accidental movement of said contact member upon its pivot to cause said member to follow the correct path during the different movements thereof.

46. In combination, a frame having a guideway therein, for receiving a carton having a flap thereon, a finger for closing said flap, means for pivotally supporting said finger and swinging it towards said carton, a cam for rocking said finger about its pivotal support to produce a movement of the end of said finger in a direction transverse to the direction of the movement of said pivotal support to cause said finger to close said flap and a second cam for guiding said finger in a different path on its return movement.

47. In combination, a frame for support

ing a carton to be filled, a reciprocating member on said frame movable into and out of position beneath said carton, means for filling a carton while supported by said reciprocating member, means for withdrawing said reciprocating member from beneath said carton after said carton has been filled, means for lowering said carton into the path of movement of said reciprocating member 10 while said reciprocating member is withdrawn so that said carton will be pushed to one side during a return movement of said reciprocating member.

48. In combination, a frame for holding a carton to be filled, a movable device for supporting said carton during a filling operation, a second device for supporting said carton, means for holding said carton in position against said second device, and means 20 for shifting said second device to move said carton out of filling position after said carton has been filled.

49. In combination, a frame having a pocket therein, means for moving a carton into said pocket, means for filling said carton while in position in said pocket, a plunger for supporting said carton in said pocket while it is being filled, a bifurcated member movable into engagement with said carton 30 on opposite sides of said plunger, hooks for engaging said carton and holding said carton in position on said bifurcated member, and means for lowering said bifurcated member and hooks to transfer the carton from said 35 filling pocket while said plunger is withdrawn from supporting position.

50. In combination, a frame, mechanism on said frame for closing the flaps of a carton, a reciprocating member for moving cartons to said closing mechanism, and means controlled by said reciprocating member for operating a portion of said closing mechanism.

51. In combination, a frame having a guideway thereon, a device for moving cartons along said guideway, mechanism on said frame adjacent said guideway for tucking in the closing flaps of said carton, and means on said moving device for controlling the 45 operation of a portion of said tucking mechanism.

52. In combination, a frame having a filling pocket therein, means for moving a carton into said pocket, means for placing an article into said carton while in said pocket, a plunger movable into and out of position to support said carton in said pocket, means for lowering said carton out of said pocket when said plunger is withdrawn from supporting position, tucking mechanism for closing said carton, and means controlled by the operation of said plunger for controlling a portion of said tucking mechanism.

53. In a wrapping machine, means for inserting an article into a carton, and means

for forming said article prior to its insertion so that said article will assist in guiding a closing portion of said carton into closed position.

54. In combination, mechanism for inserting an article into a carton, and means for forming an inclined surface on said article to assist in guiding a closing flap for said carton into closed position. 70

55. In combination, mechanism for inserting an article into a carton, and means for compressing said article to form a beveled surface thereon for guiding a closing flap of said carton. 75

56. In combination, mechanism for inserting an article into a carton, means for engaging said article at one corner thereof to form a beveled surface on said article, and means for closing said carton comprising mechanism for tucking a closing flap within 80 the wall of said carton adjacent the beveled surface formed on said article. 85

57. In combination, mechanism for folding a wrapper about an article and means for engaging the wrapped article adjacent one corner thereof to form a beveled surface at the corner of said article. 90

58. In combination, means for folding a wrapper about an article, means for engaging said article adjacent one corner thereof 95 to form a depression at the corner of said article, means for inserting said article into a carton, and means for inserting a closing flap of said carton within the wall of said carton adjacent the depression in said article. 100

59. Closing mechanism for a carton having a closing flap provided with an angularly bent tucking portion at one edge thereof, said mechanism comprising means for engaging said closing flap to resiliently hold 105 said flap in closed position, means for engaging said tucking portion to bend a portion of said flap away from the closed position against the resiliency of said flap, and means for adjusting said tucking portion of 110 said flap relative to said carton while so held.

60. In combination, means for engaging a closing flap of a carton adjacent the edge of 115 said flap secured to said carton, means for withdrawing the entire free edge of said flap away from said carton, and means for adjusting a tucking portion on the free edge of said flap into position to enter within the wall of said carton while the free edge 120 of said flap is held partially open.

61. Mechanism for closing a carton having a closing flap hinged at one side to said carton, said mechanism comprising 125 means for engaging said flap adjacent the hinged edge thereof to press said flap towards its closed position, means for engaging a projecting portion of the free edge of said flap to form said projecting portion into a tucking flap and for holding said closing 130

- flap partially open, and means for adjusting said tucking flap into closing position while said closing flap is so held.
62. In combination, a support for a carton having a closing flap thereon, a device for engaging said closing flap adjacent one edge thereof for pressing said closing flap into closed position, means for springing said closing flap backwardly against said holding device, and means for adjusting a tucking portion of said closing flap into position to enter said carton while said holding flap is held partially open by said holding means. 70
63. In combination, a support for a carton having a closing flap thereon, means for engaging said closing flap and partially closing the same and means for moving, said engaging means out of contact with said closing flap after it has been partially closed to permit the resiliency of said flap to adjust said flap relative to said carton prior to the complete closing of said flap. 80
64. In combination, a support for a carton to be closed, means for engaging a closing flap on said carton to resiliently hold said flap in closed position, mechanism for closing said flap, and means for releasing said flap from said closing mechanism after it has been partially closed to permit said flap to adjust itself under the resilient pressure thereon. 90
65. In combination, a support for a carton having a closing flap hinged at one edge of said carton, means for folding said flap against said carton so that the free edge thereof projects beyond said carton means for engaging said flap adjacent the hinged edge thereof for resiliently retaining said flap in closed position, mechanism for bending the projecting portion of said flap over a corner of said carton to form a tucking flap and for moving said tucking flap backwardly against the resiliency of said closing flap to bring the inner edge thereof beyond the side of said carton to be closed, a device for engaging said tucking flap to move it into position to enter said carton, and means for pressing said tucking flap into closed position. 100
66. In combination, a support for a carton having a closing flap thereon provided with a tucking portion, means movable toward and away from said carton for swinging said closing flap into and out of closed position, and means supported independently of said flap swinging means and movable transversely thereto for adjusting said tucking flap relative to said carton. 115
67. In combination, a support for a carton having a closing flap hinged at one edge thereof to said carton and having a tucking flap connected at the free edge thereof, means movable transversely to the face of the carton to be closed for swinging said closing flap into and out of closing position, and means having a fixed distance from the plane of said face but movable in the direction thereof for adjusting the tucking flap into position to enter said carton. 125
68. In combination, a support for a carton to be closed, a reciprocating member having a plurality of devices thereon for engaging a closing flap of said carton, a supplementary device having fingers projecting between the engaging devices on said reciprocating member to assist in the closing of said flap and means for retaining said supplementary device in position independently of the reciprocating movement of said member. 130
69. In combination, means for folding an unfolded flat carton blank into the form of an open tubular carton, means external of said carton for supporting the same during said folding operation, and means for subsequently closing both ends of said carton. 140
70. In combination, means for folding a flat unfolded carton blank having tucking end flaps thereon into the form of an open tubular carton, means other than the parts of said blank for holding said blank in tubular formation, and means for subsequently closing and tucking the end flaps of said carton. 150
71. In combination, means for folding a flat unfolded carton blank into the form of an open tubular carton, means for inserting material into said carton while closures for both ends thereof are open, and means for subsequently closing the ends of said carton. 160
72. In combination, means for folding a flat unfolded carton blank having end flaps thereon so that parts of said blank form the side walls of an open carton, means external of said carton for supporting the same during said folding operation, means for inserting material into said carton, and means for subsequently closing the end flaps of said carton. 170
73. In combination, means for folding toward one another, opposite portions of a flat sheet of material shaped to form a blank for a carton so that parts of said sheet are folded into position to constitute the side walls of a carton, means external of said carton for supporting the same during said folding operation, means for inserting material into said carton, and means for subsequently folding the remaining portion of said sheet to close the ends of said carton. 180
74. In combination, means for folding a flat sheet of material shaped to form the side walls and end flaps of a carton so that the side walls of said carton are first brought into position while the ends of said carton remain open, means external of said carton for supporting the same during the folding operation means for inserting ma- 190

terial into said carton, and means for subsequently closing the end flaps of said carton.

75. In combination, means for partially wrapping material to be enclosed in a package, means for placing the partially wrapped material in a carton, and means for completing the wrapping of the material after the material has been placed in the carton.

10 76. In combination, means for partially enfolding material in a wrapper, means for placing the partially enfolded material in a carton, and means for completing the folding of the wrapper about said material while 15 the material is in place in the carton.

77. In combination, means for partially wrapping material to be enclosed in a package, means for inserting the partially wrapped material in a carton, and means 20 for completing the wrapping of said material during the closing of said carton.

78. In combination, means for partially enfolding material in a wrapper, means for inserting the partially enfolded material in 25 a carton having closing flaps, and mechanism for closing the flaps of said carton and simultaneously completing the folding of said wrapper about said material.

79. In combination, means for partially 30 folding a wrapper about material to be enclosed in a package, means for inserting the partially wrapped material into a carton having end flaps so that a part of said wrapper will take a position adjacent one 35 of said flaps, and means for closing said flap after said material is in said carton and for simultaneously folding the portion of the wrapper adjacent said flap into position to complete the wrapping of said material.

40 80. Mechanism for closing a carton having a flap provided with a tucking portion, said mechanism comprising means for partially inserting said tucking portion in position, and releasing said tucking portion to permit the resiliency of said flap to adjust said 45 tucking portion, and means for completing the closing operation subsequent to said adjustment.

81. Mechanism for closing a carton having 50 a closing flap provided with a tucking portion, said mechanism comprising means for partially inserting said tucking portion, and releasing said partially inserted tucking portion to permit self-adjustment thereof, and means for completing the insertion of said tucking portion after the release of said adjustment.

82. Mechanism for closing a carton having 55 a closing flap provided with a tucking portion, said mechanism comprising means for engaging said flap at a position removed from said tucking portion to resiliently hold said flap in closed position, means for bending said flap to bring the tucking portion

65 into position to enter said carton and free-
ing said flap while in said position to permit self-adjustment of said tucking portion under the resiliency of said flap, and means for completing the insertion of said tucking portion subsequent to said self-adjustment.

70 75 83. In combination, mechanism for forming an open carton from a flat unfolded blank, said forming means operating entirely from the outside of said carton leaving the interior thereof empty, means for inserting an article into said carton while it is still open, and means for subsequently closing said carton.

84. In combination, mechanism for forming a tubular carton from a flat unfolded 80 blank, said forming means operating entirely from the outside of said carton leaving the interior thereof empty, an end of said carton when formed remaining open, means for inserting an article into said carton through the open end thereof, and means for subsequently closing said open end.

85. In combination, mechanism for forming a tubular carton from a flat unfolded 90 blank having closing flaps for the ends thereof, said forming means operating entirely from the outside of said carton leaving the interior thereof empty, means for inserting an article into said carton through one end thereof while said carton continues 95 in open tubular formation, and means for subsequently closing said end flaps.

86. In combination, means for supporting a flat unfolded carton blank with the wall portions thereof in substantially the same 100 plane, means operating entirely from the outside of said carton for folding said blank to bring the wall portions thereof into angular position relative to one another to form an open tubular carton, means for filling said carton through one end thereof while said end continues to remain open, and means for subsequently closing said end.

87. In combination, means for folding 110 into tubular formation an unfolded blank having end flaps thereon, means for closing said end flaps, and means engaging the exterior of said carton for retaining said blank in tubular form while said end flaps are being closed.

88. In combination, means for folding 115 into tubular form, a blank having end flaps thereon and having the periphery thereof unattached to other parts of said blank, means disposed entirely outside of said tubular form for holding said blank in tubular form, and means for closing said end flaps while said blank is so held.

89. In combination, means for folding 120 into tubular form, a carton blank having closure flaps thereon, by folding the parts successively from one edge of said blank toward the other, means for closing said flaps,

and means for retaining said blank in tubular form during the closing of said flaps.

90. In combination, means for folding a carton blank having closure flaps thereon, 5 into tubular form with portions of said blank overlapping one another, means for closing the ends of the carton thus formed, and means other than the parts of said blanks for retaining said blank in tubular 10 formation while said ends are being closed.

91. In combination, means for folding an unfolded flat carton blank into the form of an open tubular carton, means for filling said carton, means other than the parts of said 15 carton for retaining said blank in tubular formation during the filling thereof, and means for closing the ends of said carton after said carton is filled and while said carton is still held in tubular formation.

92. In combination, means for folding a carton blank having closing flaps thereon into tubular formation to provide a carton, means other than the parts of said carton for holding said blank in tubular formation 20 in position for filling, means for filling said carton while so held, and means for closing said flaps while said carton is held in tubular formation in filling position.

93. In combination, means for folding a 30 flat unfolded carton blank into tubular formation to bring opposite edges thereof into overlapping relation to one another to provide a carton, said blank having a closing flap with a tucking portion thereon, means 35 for retaining said blank in tubular formation, means for filling said carton while so retained, and means for closing said flap and inserting said tucking portion while said blank is so retained.

94. In combination, means for folding a flat blank into carton formation with a portion thereof open to receive an article, means for inserting a partially wrapped article into the carton thus formed, and means for 45 closing said carton and a portion of the wrapper on said article together to complete the wrapping of said article simultaneously with the closing of said carton.

95. In combination, means for folding a 50 blank to form a carton thereof, means for inserting an article having a wrapper partially folded thereabout into said carton, and means for closing said carton together with a portion of said wrapper to complete the 55 folding of said wrapper and the closing of said carton at one operation.

96. In combination, means for folding a flat carton blank having a closure flap thereon into the form of a carton with said flap 60 open, means for inserting an article having a wrapper partially folded thereon into said carton, and means for closing said flap and the unfolded portion of said wrapper together into closed position.

97. In combination, means for folding a 65 flat blank having a closure flap thereon into carton formation, means for partially wrapping an article, means for inserting said partially wrapped article into said carton and for bringing an unfolded portion of the 70 wrapper into registration with said closure flap, and means for folding said closure flap and unfolded portion of said wrapper together to complete the folding of said wrapper 75 and to close said carton.

98. In combination, mechanism for folding a blank into tubular formation with opposite edges thereof overlapping one another to provide a carton with open ends, said blank having a flap thereon for closing an 80 open end of said carton, upper and lower contact members for retaining said blank in folded formation, means for filling said carton while so retained, and means for closing said flap while said blank is so retained. 85

99. In combination, mechanism for folding a blank into tubular formation to provide a carton, said blank having closing flaps thereon, means for partially closing said flaps in one position, means for transferring 90 said carton to a different position, means for further closing said flaps in said different position, and oppositely disposed contact members for retaining said blank in tubular formation during the transfer 95 thereof.

100. In combination, means for folding a flat unfolded carton blank into tubular formation to provide a carton with overlapping portions, said blank having closure 100 flaps thereon, spaced contact members for retaining said blank in tubular formation, and means for shifting the position of said blank while held between said spaced contact members to retain said blank in tubular 105 formation.

101. In combination, means for folding a flat unfolded carton blank into tubular formation with parts thereof overlapping one another and unattached, said blank having closure flaps thereon, spaced contact members for retaining said blank in tubular formation, means for filling the carton formed by said blank, means for partially closing the flaps of said carton while said carton is 110 in one position, means for shifting the position of said carton while retained between said spaced contact members, and means for completing the closing of said carton in a different position while said carton is still so 115 retained.

102. In combination means for folding a flat sheet of material shaped to form the side walls and end flaps of a carton so that the side walls of said carton are first brought 120 into folded position while the ends of said carton remain open, said folding means operating entirely from the outside of said 125

carton to leave the interior thereof unobstructed, and means for subsequently closing the end flaps of said carton.

103. In combination means for folding an unfolded flat carton blank having end tucking flaps thereon, into the form of an open tubular carton with said tucking flaps at opposite ends thereof, and means for subsequently closing said tucking flaps.

104. In combination means for folding an unfolded flat carton blank having a tucking flap thereon, into the form of a tubular carton with opposite portions thereof open, and means for subsequently closing said tucking flap at one of said open portions.

105. In combination means for folding an unfolded flat carton blank having end tucking flaps thereon, into the form of a tubular

carton with its opposite ends open, and means for subsequently closing said tucking flaps to close said open ends.

106. In combination a single machine comprising means for folding a flat unfolded carton blank into the form of an open tubular carton, said folding means operating entirely from the outside of said carton to leave the interior thereof unobstructed, means for inserting material into said carton while said blank is still open and contained in said machine, and means for subsequently closing the ends of said carton while said blank is still contained in said machine.

In testimony whereof I have signed my name to this specification on this 29 day of July A. D. 1920.

MICHAEL J. MILMOE.
